2 Claims. (Cl. 273—82)

ABSTRACT OF THE DISCLOSURE

A bowling pin having a hollow metal core and a plastic coating over the core. The core has weakened areas above and below the impact area in the belly of the pin so that the belly flexes inward under impact with a bowling ball to increase the impact time.

The disclosure

This invention relates to an article having a hard core and intended for use under conditions wherein the core is subjected to impact forces. More particularly, this invention relates to bowling pins having hollow, rigid cores and to the scoring characteristics of such pins.

It is a general object of this invention to provide a new and useful article of manufacture including a novel hollow, hard core member of a configuration providing a desired flexibility in the article of manufacture.

It is another object of this invention to provide new and useful bowling pins having hollow, hard cores and having improved scoring characteristics.

Still another object of this invention is to provide a new and useful bowling pin core which is generally rigid, but flexible in the belly region under impact conditions.

Yet another object of this invention is to provide a bowling pin having a generally rigid, hard inner core with sufficient flexibility in the belly region to extend the contact time of an impacting bowling ball.

Further objects will become readily apparent from the following detailed description taken in connection with the accompanying drawing, in which:

The figure is a vertical section through an embodiment of a bowling pin of this invention.

While an illustrative embodiment of the invention is shown in the drawings and will be described in detail herein, the invention is susceptible of embodiment in many different forms, and it should be understood that the present disclosure is to be considered as an exemplification of the principles of the invention and is not intended to limit the scope to the embodiment illustrated.

Illustrative of articles of manufacture provided by the present invention having hard cores which receive impacts during use, are bowling pins which are intended to be used in bowling games, such as tenpins, and are to be struck by a ball in the manner normally occurring during such bowling games. In general, this invention provides flexibility in the impact area of the article under impact conditions, giving a longer contact time. In the instance of bowling pins, a plastic-coated hollow metal core generally has scoring characteristics different from those of a maple core pin and show very definite scoring weaknesses in both the thin and heavy-hit areas in the game of tenpins.

Before a synthetic pin, such as the plastic-coated hollow metal core pin, can receive approval of the American Bowling Congress, the major regulatory body with respect to bowling pin specifications, the pin must score like a sound, hard maple pin. Thus, the hard maple pin is considered as the standard in the bowling industry.

The increased impact time, provided by the greater flexibility in the belly region of the core in bowling pins

2

prepared in accordance with the present invention, results in improving the scoring characteristics of the pins for bringing them more in line with the scoring characteristics of a maple pin. Additionally, the longer contact time permits transfer of the force from the ball under impact over a longer period of time, resulting in improved durability and improved sound characteristics.

Referring now to the figure, there is illustrated an embodiment of the invention including a bowling pin core with a flexible belly. The bowling pin has a hard, hollow core 12 made of a hard material, e.g., a light-weight metallic material such as aluminum, magnesium, alloys of aluminum, alloys of magnesium, or a high-impact plastic material such as high-impact polystyrene, polyesters, or the like. Other usable hard core materials may be apparent to those in the art. The core is covered by a coating 13.

A bowling pin base member 14 is secured to the bottom of the pin through a central bore in core 12 and is held in place by a mass of plastic material 15 solidified in situ. The amount of plastic material 15 may be adjusted to give proper balance to the bowling pin. A top pin plug 16 is secured by adhesives or the like in a central bore in the top of the pin core 12. Coating 13, base 14, and top plug 16 define a continuous outer surface corresponding to the outer surface configuration of a regulation bowling pin.

It is common in the art to refer to the various portions of a bowling pin in terms of the head, neck, shoulder, belly, base or the like. In the drawings, the general neck area is shown within the bracket indicated by reference numeral 17 while the general shoulder, belly and base areas are generally bracketed and indicated by reference numerals 18, 19 and 20 respectively. These portions of the bowling pin will be referred to hereinbelow.

Core 12 is of a usual core configuration above the outward deviation at the bottom of the neck or top of the shoulder area indicated generally by reference numeral 23. The normal core configuration for the pin core is also included in the central belly area between ridges identified by reference numerals 24 and 25. Between reference numerals 23 and 24 the pin core tapers slightly to a weakened or flexible thin area indicated at 26 and from area 26 the core tapers back to its normal thickness at ridge 24. Also, below ridge 25 the core tapers to a weakened or flexible thin area shown generally by reference numerals 27 and then tapers back to its usual thickness in the base area of the core structure. The weakened areas 26 and 27 are circular areas extending around the pin core, respectively above and below the impact region of the core belly, and can be the thinnest portions of the core, e.g., as in the form illustrated. The weakened areas permit flexing of the impact region under impact conditions, the core generally flexing inwardly from weakened areas 26 and 27 under the impact and thereafter returning to its original condition. The weakened areas 26 and 27 may be formed by slight thinning of the core wall above and below the impact area of the belly, and said areas may function as hinges from which the belly flexes inward under impact. Beyond these thinner weakened areas the core returns to its usual configuration.

Coating 13 is a resilient coating material and is preferably an elastomeric composition. The coating may be composed, for example, of 100 parts by weight of a resin marketed under the tradename Adiprene L-100, 9 parts by weight of castor oil and 3.2 parts by weight of 1,2-butane-diol. The Adiprene resin is a polyurethane resin and consists of a linear polymer of 1,4-butane-diol and toluene diisocyanate (e.g. 2,4-toluene diisocyanate). Other suitable coating compositions include such synthetic rubbers as butyl rubber; natural rubber may also be useful as an elastomeric coating material.

Such resilient coating materials are merely illustrative

of coating materials which may be used to provide coated articles in accordance herewith. It is to be understood that any coating material having sufficient elasticity to be formable or deformable under impact of a bowling ball is usable. More advantageously, the coating material should be sufficiently resilient to retain the outer shape of the bowling pin after repeated impacts. The coating material is soft and more elastic than the hard core and is preferably resistant to cold flow. Other usable coating materials will be evident to those in the art.

The general manufacture of the bowling pin will also be apparent from the description of the pin. The core 12 may be cast in one piece by known techniques or may be formed of spun metal by known metal spinning techniques. Coating material 13 may be applied to the formed pin core by known molding techniques as an uncured mixture of resin ingredients and may thereafter be cured for a time and at a temperature sufficient to solidify the resin mixture, depending on the elastomeric material used.

For example, the specific coating material of Adiprene L-100, castor oil and 1,4-butane-diol, is cured for about three hours at about 285° F. to a Shore A 46 hardness. The resulting structure, having the coating cured on the bowling pin core, is then turned for trimming the coating material to a size slightly smaller than the regulation bowling pin size. An outer protective coating 13a is then applied to bring the bowling pin up to regulation size. The coating 13a functions to protect the pin against discoloration, e.g. by dirt, and may serve to reduce the coefficient of friction on the outer pin surface. The outer coating 13a may be a conventional plastic coating for bowling pins, e.g. nitrocellulose or ethylcellulose lacquers, cellulose acetate and/or butyrate, polyurethane lacquer, etc.

The bowling pins of the present invention may be handled and used in the same manner as the maple core bowling pins. Under impact during the game of bowling, the flexibility of the pin provided by the core weakness in the belly area permits the ball to travel further into the pin for increased contact time. Such increased contact time greatly lessens or eliminates the scoring weakness in both the thin and heavy-hit areas, which weakness appears to be inherent in hollow, metal core bowling pins. In addition, the longer contact time permits transfer of the force

from the ball impact over a longer period of time for improved durability and improved sound characteristics.

We claim:

1. A bowling pin comprising a hollow metal core and a resilient coating over said core bringing said core up to regulation bowling pin size, said hollow metal core comprising a thick metal core extending from the top of the pin downward through at least the major portion of the neck region of the pin, a tapering core wall extending thence downward and thinning to a first relatively weaker portion above the plane of impact points of core, the core wall thence tapering to a thicker portion at the impact region of the belly of the core, said wall thence thinning below the impact region to a second relatively weaker portion and said wall thence thickening from said second weak portion to the base of the pin core, said first and second weak portions being thinner than any other portion of the pin core wall so that when the pin is impacted by a ball between said first and second weak portions, the ball impact time is increased by virtue of the presence of said first and second weak portions.
2. A bowling pin comprising a hollow, generally rigid, resilient core extending from an impact belly region into a lower base region and an upper shoulder region and including a relatively weakened, flexible and resilient portion of said core in the belly region on either side of a bowling ball impact plane contiguous with the remainder of said core, said weakened portions being resilient and sufficiently weakened to increase the amount of flexing of the belly area and thereby increase the ball impact contact time of a ball impacting at said plane, and a resilient coating on the exterior of said core, each of said weakened portions having a wall thickness less than the wall thickness of the adjacent portions of the core in the base and shoulder regions.
